CLAIM

The ornamental design for a mixing console, as shown and described.

DESCRIPTION

FIG. 1 is a front perspective view of a mixing console showing the new design;

FIG. 2 is a front view of the mixing console;

FIG. 3 is a rear view of the mixing console;

FIG. 4 is a top view of the mixing console;

FIG. 5 is a right side view of the mixing console; and,

FIG. 6 is a left side view of the mixing console.

The difference in shading in the figures indicates a contrast of appearance and does not depict any particular color, texture, or material.

The broken lines in the figures are for environmental purposes only and form no part of the claimed design.
